UNITED STATES PATENT OFFICE

OTTO WEINSTEIN, OF BOSTON, MASSACHUSETTS, ASSIGNOR TO STANDARD NECKWEAR COMPANY, A CORPORATION OF MASSACHUSETTS

BOW NECKTIE

Application filed September 21, 1927. Serial No. 220,955.

This invention relates to neckties and has particular reference to an improvement in bow ties similar to that disclosed in my Patent Number 1,596,782, issued August 17, 1926.

The primary object of the present invention is to provide a bow tie embodying the advantages set forth in the above mentioned patent, and in addition thereto which shall embody resilient means for retaining the fluffed and full appearance of the bow, even after severe usage and wear. It is well known that bow ties, when first made up, present a full or fluffed effect, that is the edges of the tie extending outwardly from the knot 15 are well rounded and the ends of the bow present a well rounded turn where they double back to the knot, but these desirable effects are soon lost after short wear, due to the chin tending to crush the bow so that in 20 a short time, the upper edges particularly, present substantially a straight line from knot to outer edges, and similarly the rounded ends flatten out to a sharp crease.

These disadvantages are overcome and the 25 freshness of the tie greatly preserved by incorporating in each rounded end portion of the tie a resilient strip of material such as sheet rubber which tends to retain the material in its original shape, even after repeated crushings incident to wear.

In the drawing accompanying and forming a part of this application,

Fig. 1 is an elevation of a tie constructed in accordance with my invention;

Fig. 2 is a fragmentary perspective view with parts turned back to reveal the construction of the tie fabric; and

Fig. 3 is an enlarged, vertical sectional view taken on the line 3—3 of Fig. 1.

Broadly considered, my invention consists in inserting a sheet of resilient material in any style of preformed bow tie so that such resilient material will be folded about the ends of the bow, as indicated in dotted lines in Fig. 1. In the present instance, for purposes of illustration and also for describing a tie of preferred construction, I have shown my invention applied to a tie constructed in accordance with my aforementioned patent.

The tie material strip, as clearly shown in

Fig. 2, comprises a tubular casing formed from a rectangular piece of cloth 1, the two opposite sides of which have been folded toward each other with a substantial gap between the adjacent inturned edges 2. Positioned between the outer folded edges 3 and extending substantially the full length thereof is a lining strip 4 of a relatively soft material which serves to give body to the tie and prevent it from having a flat appearance. In some instances this strip may be omitted, if desired, as for instance where the tie cloth is of a heavy texture. Located at the spaces 5, where the tie material is doubled back on itself, are small strips of resilient material 6, such as sheet rubber. This material extends the full width of the tie tubing and preferably is of a length to extend about each complete fold 5 or turn back, although if desired, this resilient material may extend the full length of the tubing. The strips of resilient material are retained in position by a gummed tape 7 applied to the inturned edge portions of the tie material by means of heat pressing, as described in detail in my aforementioned patent. The tape 7, in addition to uniting the inturned edges of the tie cloth and retaining the resilient material 6 in position, also adds strength to the tie by reason of the texture thereof, and effects a considerable saving in the amount of tie cloth used.

A strip constructed as above described forms in a preformed bow tie, the front portion of the bow and may, if desired, also form the rear portion, but for economical reasons the rear portion is preferably formed by omitting the lining strip 4 and resilient strips 6. The tie is made in the usual or any approved manner from these strips.

A tie constructed with the resilient strips on the end portions of the finished tie serves to retain the original shape and butterfly effect of the tie, and even though subjected to repeated mashing by the wearer the tie will always present a fresh appearance, due to the tendency of the resilient material to return the folds to their original shape.

While I have shown and described my invention as applied to a bow tie constructed

in a specific manner, it will be obvious that the resilient portions could be incorporated in bow ties of any suitable or approved construction.

I claim:

- 5 1. A preformed bow tie comprising a front portion formed from a tubular casing consisting of a main piece of cloth having two opposite edges folded inwardly and toward each other, a strip of sheet rubber extending the full width of said casing and located only at spaces where the turned end portions of the finished tie are formed, and a combined securing and reinforcing element consisting of a gummed tape mounted on the exterior and on each adjacent edge portion and in contact with said strips of sheet rubber to hold the same in position, and extending lengthwise of the edges of said cloth.
- 10 10. A preformed bow tie comprising a front and a rear portion, said front portion having a pair of insets formed entirely of sheet rubber and arranged in spaced relation therein, each sheet rubber insert extending about the outer turned end portion of the tie, and means for retaining said inserts in position.
- 15 15. A preformed bow tie comprising a front and a rear portion, said front portion having a pair of insets formed entirely of sheet rubber and arranged in spaced relation therein, each sheet rubber insert extending about the outer turned end portion of the tie, and means for retaining said inserts in position.
- 20 20. A preformed bow tie comprising a front and a rear portion, said front portion having a pair of insets formed entirely of sheet rubber and arranged in spaced relation therein, each sheet rubber insert extending about the outer turned end portion of the tie, and means for retaining said inserts in position.
- 25 25. A preformed bow tie comprising a front and a rear portion, said front portion having a pair of insets formed entirely of sheet rubber and arranged in spaced relation therein, each sheet rubber insert extending about the outer turned end portion of the tie, and means for retaining said inserts in position.

In testimony whereof I affix my signature.
OTTO WEINSTEIN.
